UNITED STATES PATENT OFFICE

168,086

STOCKING

Howard Berusch, New York, N. Y., assignor to Hoburt Hosiery Corporation, New York, N. Y., a corporation of New York

Application May 28, 1952, Serial No. 19,934

Term of patent 7 years

(Cl. D47—7)

To all whom it may concern:

Be it known that I, Howard Berusch, a citizen of the United States, residing at New York, in the county and State of New York, have invented a new, original, and ornamental Design for a Stocking, of which the following is a specification, reference being had to the accompanying drawing, forming part thereof.

Fig. 1 is a side elevation of the stocking embodying my new design; and

Fig. 2 is a fragmentary rear view thereof.

I claim:

The ornamental design for a stocking, substantially as shown.

HOWARD BERUSCH.
